US00D616877S

(12) **United States Design Patent**
Kaneta

(10) **Patent No.:** **US D616,877 S**
(45) **Date of Patent:** **** Jun. 1, 2010**

(54) **MOBILE PHONE**

(75) Inventor: **Naoe Kaneta**, Tokyo (JP)

(73) Assignee: **Sony Ericsson Mobile Communications Japan Inc.**, Tokyo (JP)

(**) Term: **14 Years**

(21) Appl. No.: **29/334,060**

(22) Filed: **Mar. 19, 2009**

Related U.S. Application Data

(62) Division of application No. 29/300,694, filed on Apr. 28, 2008, now Pat. No. Des. 596,630.

(57) **CLAIM**

The ornamental design for a mobile phone, as shown and
described.

DESCRIPTION

FIG. 1 is a perspective view of a mobile phone showing my
new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof, in the open position;

FIG. 8 is a front elevational view thereof; and,

FIG. 9 is an enlarged perspective view of the claimed portion
of the mobile phone shown in FIGS. 1-9.

The broken lines showing the remainder of the mobile phone
are directed to environment and are for illustrative purposes
only; the broken lines form no part of the claimed design.
